United States Patent Office.

JOHN ROSS, OF SAN FRANCISCO, CALIFORNIA.

Letters Patent No. 100,193, dated February 22, 1870.

IMPROVED BOAT-DETACHING APPARATUS.

The Schedule referred to in these Letters Patent and making part of the same.

To all whom it may concern:

Be it known that I, JOHN ROSS, of the city and county of San Francisco, State of California, have invented an Improved Boat-Detaching Apparatus; and I do hereby declare the following description and accompanying drawings are sufficient to enable any person skilled in the art or science to which it most nearly appertains, to make and use my said invention or improvements without further invention or experiment.

My invention relates to that class of apparatus used for instantaneously detaching boats when it is necessary to free them from the tackle after lowering; and

It consists of two strong bent pins, one at either end of the boat, each having at one end a loop or head, by which to attach a chain, while the other end extends through an eye at the bottom of the block, and through another attached to the boat.

The chains from the heads pass down to the bottom of the boat, and along to the center, where they pass around a sort of capstan or upright shaft, having a crank at the top, and above the thwart, by which to turn it.

When the boat is secured, a pin passes through the thwart, so that the crank bears against it, and is prevented from turning.

To detach the boat, this pin is drawn, and the axle turns around, unwinding the chain, and allowing the ends of the pins to be freed from the eyes in the ends of the boat, after which they will both be drawn through the eyes in the block, and the boat will fall into the water.

Referring to the accompanying drawings for a more complete explanation of my apparatus.

Figure 1 is a longitudinal vertical section of the boat attached to the blocks.

Figure 2 is a similar view, the boat being detached. A is a part of the side of a vessel, or point where the davits B B are placed.

The boat C is hung from the davits by the ordinary tackle D.

The connection between the tackle and the boat consists of a stout pin, E, at each end somewhat

curved, and having an eye or head, a, to which the chain F is fastened.

The end b of the pin is extended to such a length as to pass through an eye or staple, c, at the bottom of the block, and thence through another staple, d, which is fastened to the boat.

The chain F thus holds one end of the pin E, while the other end is detained by the staple d, so that it forms a connecting-link as long as the boat is kept close enough to the blocks to prevent the end b from leaving the staple d.

The chain F passes through d, and thence down along the bottom of the boat to a point near the center, where it is passed around an upright spindle or axle J, having a journal at the bottom and another in the thwart G, or other support, through which it passes. It is turned by a crank, I, at the top, and, by winding up the chain, and passing a pin, H, through the support G in front of the crank I, the boat is secured.

In order to detach the boat after lowering, the pin H is withdrawn, and the chain allowed to unwind till the ends b of the pins E pass out of the staple d, when they will instantly turn, as shown in fig. 2, and pass through the eyes c of the blocks, allowing the boat to fall on an even keel.

This apparatus is very simple, is easily attached to any boat, and is very efficient.

Having thus described my invention,

What I claim, and desire to secure by Letters Patent, is—

In combination with the device consisting of the bent pin E, eye d, and chain F, the spindle J, crank I, and pin H, for drawing, holding, and releasing together the chains F from the two ends of the boat, substantially as and for the purpose set forth.

In witness whereof I have hereunto set my hand and seal.

JOHN ROSS. [L. s.]
